COMBINED DRESSER AND LUGGAGE RACK

Louis Elliott Frey, Los Angeles, Calif.

Application May 19, 1958, Serial No. 50,972

Term of patent 14 years

(Cl. D33—6)

Fig. 1.

Fig. 2.

Fig. 3.

Fig. 1 is a perspective view of a combined dresser and luggage rack embodying my new design.

Fig. 2 is a front elevational view of the same.

Fig. 3 is an end view of the same.

The back is plain and unornamented.

I claim:

The ornamental design for a combined dresser and luggage rack, substantially as shown, and described.
